UNITED STATES PATENT OFFICE

FRANCESCO GIOVANNI GARABELLO, OF TURIN, ITALY

INTERNAL-COMBUSTION ENGINE

Application filed June 3, 1929, Serial No. 367,904, and in Italy June 21, 1928.

The present invention has for its object a sealing device for rotary distributors of internal combustion engines, pumps and the like.

5 In accordance with the present invention the seal of the distributor is secured by means of a frame mounted to move in a seat for the distributor, said frame being forced on the rotary distributor by the compression or explosion pressure, while along the frame edge the seal is secured by a flexible member of said seat which is forced by fluid pressure on the edge of said frame.

10 On the annexed drawing is illustrated by way of example an embodiment of the present invention as applied to an internal combustion engine, and

15 Figure 1 is a section of the engine along the cylinder and crank shaft axes;

20 Figure 2 is a transverse section to an enlarged scale of the cylinder head and of the distributor on the line 2—2 of Fig. 1;

25 Figure 3 is a bottom view of the separate sealing frame.

In the illustrated embodiment, the engine comprises a casing 1 in which is mounted a crank shaft 2 actuated by a connecting rod 5 and a piston 3 mounted to reciprocate in cylinder 4.

30 On the head of the engine cylinder 4 which has a top mouth 6, is located a casing 7 in which a rotary distributor 9 is mounted to rotate by means of ball bearings 8; said distributor 9 is driven by the engine shaft 2 by means of a gearing 10, 11, 12, 13, 14 and connects timely the mouth 6 of the cylinder with a duct 15 leading from carburetter (not shown) and with exhaust 16.

35 In chamber 7, around the cylinder mouth 6, a sealing frame 18 is mounted to move in a recessed seat 17, it being able to move in the direction of the engine cylinder axis; the top cylindrical and concave portion of said frame bears on the surface of the distributor 9 while it has a mouth 6' registering with mouth 6 of the cylinder.

40 Springs 19 located in recesses provided on the cylinder head, hold the frame 18 permanently forced on the distributor surface. Frame 18 has ducts 20 passing through it for

providing an oil flow therethrough by means of a suitable pump (not shown) and tubes 21—22, for the purpose of cooling frame 18.

Said frame 18 has in its opening a surface 18' parallel with the cylinder axis and a rib 18'' projecting towards inside of mouth 6' (Figs. 2 and 3).

The mouth 6 of the cylinder is encircled by a peripheral tongue 23, which may be secured on said mouth or may be obtained from the material providing the cylinder head, and the projecting portion of said tongue bears on the surface 18' of the frame.

In operation, springs 19 hold the frame 18 permanently forced on the surface of distributor 9 to prevent rattling and during the compression and explosion periods the gases under pressure operative in the cylinder 4 also act on the edge 18'' of the frame 18 and force

55 said frame with heavier action on the distributor to secure seal along the periphery of the mouth 6' of the frame on which the surface of the distributor slides; at the same time the pressure operates outwardly on the tongue 23 and forces it on the portion 18' of the frame 18 to secure the seal between the seat 17 of the cylinder and the frame and prevent gases from leaking through the gap existing between the bottom face of the frame 18 and the seat 17 in which it is mounted.

60 A satisfactory seal is thus secured while the distributor 9, being mounted in bearings 8, cannot be forced on the surface of its seat 7 opposite the mouth 6 of the cylinder.

65 The tongue 23 may be separate from and fastened on the mouth 6 of the cylinder as illustrated, or it may be obtained from the material providing the cylinder.

70 What I claim as my invention and desire to secure by United States Letters Patent is:—

75 1. In a reciprocatory machine a cylinder, a casing on said cylinder, said cylinder having a mouth opening in said casing and a recessed seat encircling said mouth, a rotary distributor in said casing, means for driving said distributor, a frame loose in said seat and encircling said mouth and having a surface contacting with said distributor and a surface subject to the cylinder pressure, and

a tongue on said cylinder mouth subject to cylinder pressure and contacting with the surface of said frame.

2. In a reciprocatory machine a cylinder, a casing on said cylinder having a mouth opening in said casing and a recessed seat encircling said mouth, a rotary distributor in said casing, means for driving said distributor, a frame loose in said seat and having an orifice registering with said mouth said frame having a surface contacting with said distributor and a second surface parallel with the direction of the free motion of said frame in said seat, a pressure receiving rib on said frame around said orifice, and a pressure receiving tongue on said seat contacting with said second frame surface.

3. In a reciprocatory machine a cylinder, a casing on said cylinder having a mouth opening in said casing and a recessed seat encircling said mouth, a rotary distributor in said casing, means for driving said distributor, a frame loose in said seat and having an orifice registering with said mouth, said frame having a surface contacting with said distributor and a second surface parallel with the direction of the free motion of said frame in said seat, a pressure receiving rib on said frame around said orifice, a pressure receiving tongue on said seat contacting with said second frame surface, and springs forcing said frame on said distributor.

4. In a reciprocatory machine a cylinder, a casing on said cylinder having a mouth opening in said casing and a recessed seat encircling said mouth, a rotary distributor in said casing, means for driving said distributor, a frame loose in said seat and having an orifice registering with said mouth, said frame having a surface contacting with said distributor and a second surface parallel with the direction of the free motion of said frame in said seat, a pressure receiving rib on said frame around said orifice, a pressure receiving tongue on said seat contacting with said second frame surface, springs forcing said frame on said distributor, said frame having holes allowing a circulation of cooling fluid through said frame.

In testimony whereof I have signed my name to this specification.

FRANCESCO GIOVANNI GARABELLO.
